JOHN L. LAY OF BUFFALO, NEW YORK, ASSIGNOR TO HIMSELF AND
H. O. PERRY, OF SAME PLACE.

Letters Patent No. 66,976, dated July 23, 1867.

IMPROVEMENT IN STEAM ENGINES.

The Schedule referred to in these Letters Patent and making part of the same.

TO ALL WHOM IT MAY CONCERN:

Be it known that I, JOHN L. LAY, of the city of Buffalo, in the county of Erie, and State of New York, have invented certain new and useful improvements in Compound Engines; and I do hereby declare that the following is a full and exact description thereof, reference being had to the accompanying drawings, making part of this specification, in which—

Figure 1 is a central vertical section of my improvements.

Figure 2 is a front elevation with the valve and portion of the steam-chest removed to show the ports.

Figure 3 is a perspective view of the valve detached.

Like letters designate corresponding parts in all the figures.

My improvements relate to that class of engines in which two cylinders, a high and a low-pressure, are combined, the exhaust steam from the former being employed to work the piston of the latter, and the steam being used expansively in both. The object is to dispense with the use of a stuffing-box intermediate between the two cylinders when abutting, or in their proximate heads when they are arranged a short distance apart, and to provide a single valve that shall suffice for operating both cylinders.

The invention consists, first, in the employment of a tube which is connected by a steam-tight joint with the intermediate head of the abutting cylinders, or with the head of the high-pressure cylinder proximate to the low-pressure when the two cylinders are separated, which tube extends through the low-pressure cylinder into the stuffing-box in the opposite head, the tube fitting around the piston-rod, which reciprocates within. It further consists in the construction of a piston-valve, provided with three pistons, which fit and work within the valve-chest, in combination with the several ports *a b c d*, and exhaust-chamber *e*, by which both cylinders are operated, substantially as hereinafter fully set forth.

In the drawings, *A* and *B* represent a high and a low-pressure cylinder, with the former arranged vertically beneath and concentric with the latter, abutting together, with a single intermediate head, *C*, for both, which is bolted to the top of a suitable frame, *D*, which supports them. *E* and *F* are respectively the pistons of the high and low-pressure cylinders, the former attached to rod *G*, which extends upward through both cylinders, and is fastened to the centre of cross-head *P*, while the latter is attached to two rods, *Q Q*, connecting with the end of the cross-head, as shown in fig. 2; and *H* is a tube or pipe (represented as screwed into the intermediate head *C*) extending upward into the stuffing-box *I* in the top head of the upper and low-pressure cylinder. This tube is made sufficiently large to permit the unobstructed reciprocations of the piston-rod *G*. This stuffing-box *I* prevents the escape through it of the steam from the high-pressure cylinder. When the two cylinders are made separate and arranged a short distance apart, the tube *H* is screwed into the inner or proximate head of the high-pressure cylinder, from whence it extends into and through the low-pressure cylinder, as before described. It is evident that this tube may be arranged so as to extend through the high instead of the low-pressure cylinder, and operate effectively, although the former arrangement is to be preferred.

From the foregoing description it is readily perceived that the use of the tube *H* dispenses with the necessity of a stuffing-box in the intermediate head of the two cylinders, which is so difficult of access, and with two stuffing-boxes when the cylinders are arranged apart. The employment of it costs but little. It is readily applied, and can with little difficulty be applied to old engines which are of the proper construction and arrangement.

J represents the steam-chest of the cylinder *A*, *K* the valve, consisting of the rod *f*, by which it is operated, to which are attached the three pistons *g h i*, which, in the reciprocations of the valve, alternately open and close the ports *a b c d*, as will be presently more particularly described. The ports *a b* lead respectively to the upper and lower ends of the high-pressure cylinder, and *c d* to the upper and lower ends of the low-pressure cylinder, as shown, while the chamber *e*, formed between the ports *c d*, into which the latter alternately open, permits the escape of the exhaust steam therefrom into the passage *m*, which communicates with the external air or conducts to the condenser.

The operation of this part of my improvement is as follows: When the valve is in the position represented in fig. 1 the port *b* is open, allowing the steam from the boiler to pass to the bottom of the high-pressure cylinder,

while the port *a* is covered by the piston *g*. The ports *a* and *b* respectively open alternately into *d c*, and *a*, now communicating with *d*, permits the steam from the upper end of the high-pressure cylinder to pass into the bottom of the low-pressure cylinder, as represented by the arrows, while the piston *h*, which in this position closes the passage between *d e*, leaves the one between *c e* open, through which the exhaust steam from the upper end of the low-pressure cylinder is permitted to escape into the passage *m*, and thence into the air or condenser, as above described. When the piston is at its opposite throw, it is obvious that the port *a* will be open and *b* covered, with a corresponding change in the other parts, causing the steam to reverse its direction, the exhaust from the lower end of the low-pressure cylinder now escaping through *d* into *e*, and thence into *m*, as before.

It is evident that my improvements are applicable to compound engines when the cylinders are arranged horizontally, and will operate with equal efficiency. The advantage of my improved valve is that a single one suffices for both cylinders, thereby saving the expense of one or more valves with the extra machinery required for operating them. An engine provided with my improvements also weighs less and occupies less space than others, which is of much importance when employed for marine purposes.

What I claim as my invention is—

1. The employment of a tube, *H*, in combination with the piston-rod *G* and cylinders *A B* of a high and low-pressure engine, substantially in the manner and for the purposes set forth.
2. I also claim the valve *K*, consisting of the rod *f* and pistons *g h i*, arranged with reference to the ports *a b c d*, and chamber *e*, substantially as specified.
3. I also claim the above-described valve, in combination with the high and low-pressure cylinders *A B*, provided with the tube *H*, the whole arranged and operating substantially as described.

In witness whereof I have hereunto signed my name in the presence of two subscribing witnesses.

JOHN L. LAY.
